MEANS FOR ELECTRICALLY REPRODUCING
SOUND

Albertis Hewitt, Pitman, N. J., assignor, by mesne assignments, to Radio Corporation of America, New York, N. Y., a corporation of Delaware

Application December 17, 1924
Serial No. 756,571

3 Claims. (Cl. 179—100.41)

This invention relates to the reproduction of sound, and more particularly to a method and means for electrically reproducing sound from talking machine records.

- 5 It has heretofore been proposed to reproduce sound electrically from talking machine records, and to amplify the reproduction by suitable means including the use of thermionic valves. These devices have been unsatisfactory in that 10 the amplification has increased the volume of foreign or irregular sounds, such as are produced by the engagement of the needle or stylus on the record, etc., as well as the volume of the pure or musical sounds.
- 15 It has also been proposed, heretofore, to dampen the vibratory elements of a sound-box to eliminate undesirable noises and irregularities of sound, such as are produced by the mechanical engagement of the sound reproducing elements.
- 20 This dampening, however, has invariably resulted in the distortion and suppression of the pure as well as the irregular sounds.

An object of the present invention is to provide a novel method and means for electrically 25 producing sounds from a record tablet so as to minimize the harsh and irregular sounds or noises while amplifying the pure sounds to any desired volume.

Another object of the invention is to provide a 30 method and means for electrically reproducing a record tablet by dampening the mechanical vibrations produced by the action of a stylus or needle cooperating with said tablet, converting the dampened mechanical vibrations into electrical vibrations, amplifying the latter, and converting the same into sound waves.

Another object of the invention is to provide, in combination, a damped stylus bar, a damped armature actuated by the bar, and 40 suitable means for amplifying the electrical vibrations produced by the damped mechanical vibrations of the stylus bar and armature.

Other objects of the invention are to provide means of the character described which may be 45 employed in combination with talking machines now in use, which are rugged in construction, and which are readily accessible for repair. These and other objects will appear more fully herein-after.

50 The invention will be readily understood by reference to the accompanying drawings illustrating one embodiment of the inventive idea, but it is to be expressly understood that the drawings are for purposes of illustration only and are not 55 designed as a definition of the limits of the in-

vention, reference being had to the appended claims for this purpose.

In the drawings,

Fig. 1 is a front elevation illustrating one embodiment of the electrical reproducer of the 60 present invention;

Figs. 2 and 3 are sectional views taken on the lines 2—2 and 3—3, respectively, of Fig. 1;

Fig. 4 is a detail sectional view, somewhat enlarged, illustrating one manner in which the 65 armature of the reproducer may be damped;

Fig. 5 is a detail perspective illustrating a preferred form of stylus bar;

Fig. 6 is a detail sectional view taken on line 6—6 of Fig. 1;

Fig. 7 is a detail view, partly in section, illustrating a portion of the stylus bar mounting;

Fig. 8 is a perspective of one of the pole pieces that may be employed in the reproducer; and

Fig. 9 is a diagrammatic view illustrating one 75 combination of elements that may be employed for carrying out the method of the present invention.

Referring to the drawings, wherein like reference characters refer to like parts throughout the 80 several views, 10 is a shell or casing of any suitable form and material that at its forward face is bent inwardly to form a circular shoulder 11. A cup 12, of any suitable material, such as aluminum, and provided with a central opening 12', is main- 85 tained in engagement with shoulder 11 in any suitable way, as by means of a cylindrical member 13. Preferably, the latter is formed of a suitable dielectric such as vulcanized rubber. The opposite or rear end of the chamber formed by the 90 member 13 is closed by a disk 14, which constitutes an insulating member, and which is maintained in position by means of a disk-like cover 15 which is removably secured to the rear end of casing 10 in any suitable manner as by means of 95 screws 16.

Mounted within the chamber formed by the elements 12, 13 and 14 described above, is a permanent magnet 17 of any suitable construction, shown as a circular magnet which is divided at 100 one side to provide spaced poles 17' that are located on the opposite sides of the medial plane of the magnet. Secured to the inner surface of each pole 17', as by means of screws 18, is a U-shaped pole piece 19 or 20 which extends radially inward 105 from its pole and which is so mounted that its limbs project toward the corresponding limbs of the other pole piece. A flattened spool 21 provided at its opposite end with flanges 21' is positioned between the limbs of pole pieces 19 and 110

20 and a suitable coil of wire 22 is wound around the spool between its flanges. Pivotally mounted by means of a hinge member 23 within the spool 21 and centrally thereof, is a flat plate 24 constituting an armature. The hinge member 23 has its opposite ends extending through openings in armature 24 and in the wall of spool 21 in a manner known in the art. The length of the armature 24 is preferably such that it extends both above and below the limbs of the pole pieces 19 and 20.

25 Suitably secured to the front face of the upper end of armature 24, and centrally thereof, is an L-shaped stylus bar 25. The upper horizontal limb 25' of this bar, which is preferably in the form of a wire to provide suitable lateral flexibility, extends outwardly through the opening 12' in cup 12, and a groove 20' may be formed in the upper surface of the inner limb of the pole 30 piece 20 to receive said horizontal limb 25'.

Any suitable means may be provided for operatively mounting the stylus bar on the casing 10. The present invention, however, includes a novel mounting which is productive of superior 25 results. In the form shown a bar 26 extends horizontally across the forward face of casing 10 and adjacent the lower portion thereof and is preferably formed integrally with said casing. Secured in any desired manner to the front face 30 of bar 26 is a knife-edge 27 which extends parallel with the axis of the bar 26 and at right angles to the axis of stylus bar 25. Symmetrically mounted on the front face of bar 26, in planes parallel to the stylus bar 25 and equidistant 35 therefrom, are a pair of T-shaped lugs 28 (see Fig. 7) which receive and retain in cooperative position a pair of U-shaped springs 29 which are suitably secured, as by means of brazing, to the opposite sides of stylus bar 25 in the plane of 40 knife-edge 27. Lugs 28, springs 29 and knife-edge 27 are so proportioned that the springs are maintained in a flexed condition, as is clearly illustrated in Fig. 6, when the stylus bar is engaged 45 with the knife-edge 27 and the springs 29 have their U-shaped ends engaged under the lugs 28. The usual stylus or needle 30 and retaining means 31 are provided at the lower end of the stylus bar 25.

50 Suitable damping means are preferably provided for dampening the natural vibration of stylus bar 25 and also for preventing whipping of the same. In the form shown, this dampening means comprises a rubber tube 32 which surrounds the stylus bar and extends from the armature 24 outwardly and downwardly to the upper edge of springs 29.

Means of any suitable type are also provided 55 for dampening the mechanical vibrations imparted to armature 24 by the cooperation of the stylus or needle 30 with a rotating record tablet, in order that the irregular vibrations or noises, such for example as are caused by the engagement of the needle on the record tablet may be 60 eliminated or suppressed and that the periodic vibrations of the pure or musical sounds only will be available for actuating the armature to 65 induce currents of variable E. M. F. in coil 22. In the form shown (Figs. 2, 3 and 4) this dampening means comprise a pair of elongated blocks 70 33, preferably formed of compressed rubber, which are interposed between the ends of the limbs of one of the pole pieces, as 19, and armature 24, said blocks being preferably secured to 75 the former, and co-act with said armature ad-

jacent the opposite ends thereof. While the drawings illustrate the use of two dampening blocks, one block for each limb of pole piece 19, it is to be expressly understood that one block may be employed on each side of the armature if desired, or other arrangement of the dampening blocks may be used.

80 Secured to the cup 12 and projecting within the magnet 17 are binding posts 34 to which are attached conductors 35 that are placed in electrical communication, in any well known manner, with the opposite ends of coil 22. Conductors 35 pass rearwardly through openings in insulating disk 14 and rear cover plate 15 to a suitable amplifying circuit such, for example, as that diagrammatically illustrated in Fig. 9, wherein the thermionic valves 36 amplify the currents produced in coil 22 and deliver said amplified currents to a loud speaker 37 of any suitable type.

85 A neck 38 (Fig. 2) of any suitable form may be formed on the rear of plate 15 to constitute means for securing the reproducer unit to a movable arm 39 (Fig. 9). This arm is mounted in any suitable way adjacent a turntable 40 that is adapted to carry the usual record tablet 41.

90 *Operation*—Rotation of the turntable 40, and consequently of the tablet 41, results in the vibration of stylus bar 25, and the vibrations of said bar are transmitted directly to the pivotally mounted armature 24. The blocks 33 dampen 95 the vibrations of armature 24 to such an extent that the irregular vibrations and noises, such as are caused by engagement of the needle with the tablet 41, are suppressed. Therefore, the dampening action of said blocks, aided by the action 100 of dampening member 32, cause the vibrations that result in pure or musical sounds, to be effective in vibrating the armature 24 to induce electrical effects or currents of variable E. M. F. in the coil 22. These induced currents are amplified 115 by the thermionic valves 36 and are converted into mechanical effects or sound waves by the loud speaker 37.

110 While the embodiment of the invention illustrated on the drawings has been described with considerable particularity it is to be expressly understood that the invention is not limited thereto, as the invention is capable of being embodied or carried out in a variety of ways, some 120 of which will now readily suggest themselves to those skilled in the art, while changes may be made in the details of construction and arrangement without departing from the spirit of the invention. For convenience of definition the 125 sounds which were originally recorded on the record tablet and which it is desired to reproduce, will be referred to as pure sounds or vibrations, whereas foreign sounds and noises resulting from the action and interaction of the mechanical elements, which are vibrated by cooperation 130 with the record tablet, will hereinafter be referred to as irregular sounds or vibrations. While the use of two thermionic valves has been 135 shown in the amplifying circuit it will be understood that this showing is diagrammatic only, and that any suitable amplifying circuit employing any desired number of thermionic valves, or other suitable means may be employed. Reference is therefore to be had to the claims hereto 140 appended for a definition of the limits of the invention.

145 What is claimed is:

1. An electrical reproducer comprising a circular magnet having laterally spaced overlapping poles, pole pieces carried by said magnet, a coil 150

- between said pole pieces, a vibratable armature extending through said coil, a stylus bar, a transmitting element operatively connecting said stylus bar and said armature, and means for damping vibrations of said stylus bar and transmitting element. 15
2. An electrical reproducer comprising a stylus bar, means for damping vibrations of said bar, a vibratable armature, a transmitting element operatively connecting said bar and armature, 20
- means for damping the vibration of said transmitting element, and means for damping the vibrations of said armature. 25
3. In an electromagnetic reproducing and recording device, means for producing a magnetic field, a coil disposed in said field, an armature pivotally mounted adjacent to said coil, a pivotally mounted stylus bar, and a flexible connection between said armature and said bar. 30
